UNITED STATES PATENT OFFICE.

JAMES F. PATTON, OF CLEVELAND, OHIO.

MANUFACTURE OF IRONING-MACHINE SHOES.

Application filed December 7, 1921. Serial No. 520,706.

To all whom it may concern:

Be it known that I, JAMES F. PATTON, a citizen of the United States, and a resident of Cleveland, county of Cuyahoga, and State 5 of Ohio, have invented a new and useful Improvement in the Manufacture of Ironing-Machine Shoes, of which the following is a specification, the principle of the invention being herein explained and the best 10 mode in which I have contemplated applying that principle, so as to distinguish it from other inventions.

In mangles or ironing machines such as have of late been largely popularized for 15 domestic in contradistinction to commercial use, as well of course as in the latter, the characteristic structural element is the heating shoe or chamber against which a rotative drum is adapted to bear, so that the articles to be ironed may be passed across the 20 surface of such shoe by the rotation of the drum. The surface of the latter is usually formed of padded fabric tightly wound or otherwise secured to the drum, while the 25 shoe is made of metal, usually cast iron, and its contacting surface is highly polished, the function of such surface being that of the highly polished surface in the familiar sad-iron. In order to secure satisfactory 30 operative results with a machine of the type in question, it is obviously necessary not only that such operative surface of the shoe be highly polished, but also that it conform accurately to the cylindrical surface of the 35 drum.

In the manufacture, however, of such shoes, no small amount of difficulty is encountered when it is attempted to machine the rough casting by ordinary methods. The 40 heating effect of the machining operation in particular I have discovered produces such a distortion or warping of the shoe, which is of relatively elongated narrow shape, that no matter how carefully the casting be 45 blocked up on the machine bed, or how carefully the actual machining operation be gauged, the result will be a surface not strictly cylindrical, or if initially so, inherent strains are produced that will subsequently manifest themselves in the assembled machine by causing the shoe to buckle slightly and so destroy the original true shape given its operative face.

The object of the present invention, accordingly, is to provide a method of finishing the surface of such an ironing machine

shoe or similar mechanical part as will avoid the difficulties just referred to, and to this end the present invention consists of the steps hereinafter fully described and particularly pointed out in the claims, the annexed drawing and the following description setting forth in detail one approved method of carrying out the invention, such disclosed mode, however, constituting but 65 one of the various ways in which the principle of the invention may be used.

In said annexed drawing:

Fig. 1 is a side elevational view more or less diagrammatic in character, illustrating 70 my improved method of finishing machine parts of the character in question; and Fig. 2 is a transverse sectional view of the mechanism or apparatus shown in Fig. 1, taken on the plane indicated by the line 2—2 on said 75 figure.

Briefly stated, my improved method of manufacture involves the use, instead of a planing, milling or shaping tool to finish the surface, of such ironing machine shoe or 80 the like, of a grinding wheel formed of a suitable abrasive, such as carborundum, such wheel being of the proper cross-sectional shape to impart the desired curvature to the surface being finished, and not only being it- 85 self rotated at a high rate of speed, but also being relatively moved back and forth over the work. In this manner the heating effect of the grinding operation is given no chance to accumulate in any one part of the work, 90 but the latter is heated approximately uniformly practically throughout its entire extent. Not only do I thus avoid any tendency for the work to become distorted during 95 the actual finishing operation, but so far as the action of the heat developed may approach that of an annealing operation, the result is uniform throughout the work and so no unusual strains remain in the latter to occasion distortion later.

The illustrative figures of the drawing show simply in diagrammatic form a reciprocable suitable bed 1, such as is employed in a planer or like type of machine, the work W being secured to such bed in 105 any approved fashion. In the case in hand, such work consists of an ironing machine shoe casting of typical cross-section as shown in Fig. 2, it being the concave cylindrical surface w of such shoe that requires 110 to be finished. The grinding wheel 2 is accordingly made of corresponding convex

22
 cylindrical form and is mounted on a suitable shaft 3 in a head 4 that may be vertically adjusted as required, the direction of movement of the bed 1 being at right angles 5 to said shaft, i. e. parallel with the axis of the surface *w*. Any suitable means for driving the arbor at a relatively high rate of speed may be provided, such for example as the countershaft 5, directly connected with 10 the arbor 3 through a belt 6 and suitable pulleys.

In operation, after the work has been secured to the bed 1, as aforesaid, the grinding wheel 2 is adjusted in proper position 15 to contact with the surface *w* and, being set in rotation, the bed 1 is thereupon moved back and forth from one end to the other so as to cause said wheel to operate on the work. The rapidity of the reciprocatory 20 movement that requires to be thus imparted to the bed will vary with the character of the work, the particular constitution of the metal composing same, its thickness, etc., but the rate of movement can be accurately 25 gauged by noting the heating effect. This, as before stated, where such reciprocatory movement is sufficiently rapid, will be substantially uniform throughout the entire extent of the work, as may be readily determined 30 by any suitable thermometric appliance. I have found that not only may the ironing machine shoe be finished very expeditiously in the aforesaid manner, but that it will be much superior to shoes as currently made by ordinary machining processes. In other words, no perceptible warping 35 or distortion will occur subsequently either during storage or under conditions of use where, of course, heat requires necessarily 40 to be applied to the shoe. This will

indicate that the inherent strains, if any remain, are uniformly distributed throughout the shoe if not actually that an annealing effect has been secured whereby such strains have been completely eliminated.

It will be understood of course, that so far as the results obtained are concerned, it is a matter of indifference whether the bed with the work be reciprocated relatively to the grinding wheel, or vice versa, so long as 50 such wheel be caused to cover the surface operated on with sufficient frequency to produce the desired result.

Other modes of applying the principle of my invention may be employed instead of 55 the one explained, change being made as regards the method herein disclosed, provided the step or steps stated by the following claim or the equivalent of such stated 60 step or steps be employed.

I therefore particularly point out and distinctly claim as my invention:—

In the manufacture of ironing machine shoes and like articles, the method of finishing the working face thereof, which consists in contacting a grinding wheel of the proper transverse contour with such face, and then simultaneously rotating such wheel and relatively reciprocating the same or the article, one with relation to the other, longitudinally of the latter at such a rate as will heat said article substantially uniformly throughout, until a temperature is finally thus produced sufficient to relieve said article of inherent strains or stresses substantially as described.

Signed by me, this 1st day of December, 1921.

JAMES F. PATTON.
